UNITED STATES PATENT OFFICE

104,817

DESIGN FOR A VEHICLE FIRE EXTINGUISHER BODY

Jay Lawrence Seat, Fairfield, Conn.

Application September 18, 1936, Serial No. 64,916

Term of patent 3½ years

To all whom it may concern:

Be it known that I, Jay Lawrence Seat, a citizen of the United States, residing at Fairfield, in the county of Fairfield and State of Connecticut, have invented a new, original, and ornamental Design for a Vehicle Fire Extinguisher Body, of which the following is a specification, reference being had to the accompanying drawing, forming part thereof.

Figure 1 is a side elevational view of a vehicle fire extinguisher body, showing my new design.

Figure 2 is a reverse side elevational view thereof, and

Figure 3 is a top plan view thereof.

I claim:

The ornamental design for a vehicle fire extinguisher body, as shown.

JAY LAWRENCE SEAT.
